[57] CLAIM

The ornamental design for dispensing figurine for a box of tissue, as shown and described.

DESCRIPTION

FIG. 1 is a top plan view of a dispensing figurine for a box of tissues showing my new design;

FIG. 2 is an end elevational view;

FIG. 3 is an end elevational view showing the end opposite that seen in FIG. 2;

FIG. 4 is a side elevational view;

FIG. 5 is a bottom plan view; and

FIG. 6 is another side elevational view.

The broken lines showing a portion of a tissue and a tissue box in FIG. 4 are for illustrative purposes only.
